UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING-MACHINE.

1,371,314.

Specification of Letters Patent.

Patented Mar. 15, 1921.

Application filed November 21, 1916, Serial No. 132,681. Renewed February 4, 1921. Serial No. 442,593.

To all whom it may concern:

Be it known that I, NILS D. LEVIN, a citizen of the United States, residing at Columbus, in the county of Franklin and State 5 of Ohio, have invented certain new and useful Improvements in Mining-Machines, of which the following is a specification, reference being had therein to the accompanying drawing.

10 This invention relates to certain new and useful improvements in mining machines and particularly to that class of mining machines which is provided with an elongated cutter arm adapted to be thrust longitudinally into the coal and to then be moved laterally across the face to under cut the coal preparatory to breaking it out of its natural bed.

The especial object of my invention is to 20 provide, in a machine of the class described, improved gearing and arrangement of parts which shall combine maximum efficiency with extreme convenience of operation.

The preferred embodiment of my invention is disclosed in the following specification and illustrated in the accompanying drawings of which—

Figure 1 is a general plan view of the machine, the cover plates being removed to 30 show the arrangement of gearing.

Fig. 2 is a side elevation of the machine illustrated in Fig. 1.

Fig. 3 is a longitudinal section along the vertical central plane of the machine.

35 Fig. 4 is a sectional view taken along the line 4—4 of Fig. 1.

Fig. 5 is a sectional view taken along the line 5—5 of Fig. 1.

40 Fig. 6 is a sectional view taken along the line 6—6 of Fig. 1.

Fig. 7 is a fragmentary sectional view taken along the line 7—7 of Fig. 1, intended to show particularly the method of holding the thrust of the master gear.

45 Fig. 8 is a fragmentary sectional view taken along the line 8—8 of Fig. 3.

Fig. 9 is a diagrammatic view illustrating the method of handling the machine about the room of the mine.

50 Fig. 10 is a diagrammatic view illustrating the method of making the sumping, or entering cut.

Fig. 11 is a diagrammatic view illustrating the method of cutting across the face of 55 the coal.

Fig. 12 is a diagrammatic view illustrating an alternative method of making the sumping or entering cut.

Fig. 13 is a detail view of the mechanism for connecting the handling drum with the 60 power elements of the machine.

Like numerals refer to similar parts in the several figures.

Referring to the drawings the numeral 1 indicates the base frame casting upon which 65 the operative parts of the machine are supported. At each side the base frame casting is attached, in any preferred manner, as by the machine screws 2, to the upwardly turned edges 3 of the skid pan 4. This skid 70 pan 4 is composed of a rolled steel plate and serves as a broad supporting base adapted to slide in any direction over the floor of the mine.

Extending longitudinally of the base 75 frame casting 1 are two downwardly projecting ribs 5 which are joined at intervals by the cross webs 6 to form a rigid support for the cutting mechanism. The outer faces of the ribs 5 slidably engage the rearward 80 part of the U shaped bar 8 which constitutes the foundation of the cutter arm 9. Secured to the U shaped bar 8 by suitable rivets are the top plates 10 and bottom plates 11, the edges of which project beyond the outer face 85 of the bar 8 to form guide ways in which travels the cutter chain 12. The inner edges of the top plates 10 also project beyond the inner face of the bar 8 to form flanges which engage the longitudinal grooves 7 of the 90 ribs 5 to support the weight of the cutter arm. The chain 12 is of the usual type having renewable cutter bits 13 by which the coal is cut. Guide strips 14 are riveted along the edges of the plates 10 and 11 to 95 engage the guide flanges of the cutter chain links to hold them in place in the guide ways. A plate 15 extends from side to side of the cutter frame below the supporting ribs 5 to maintain the proper relation between the rearward ends of the U shaped 100 bar 8.

Provision is made for the longitudinal adjustment of the cutter frame, relative to the base frame casting 1, to regulate the tension of the cutter chain, by an adjusting screw 16 the rearward end of which abuts upon the web 17 of the main frame casting. This adjusting screw 16 is fitted with a nut 18 having a flange 19 which engages suitable 110

notches in the plates 10 and 11 to maintain a fixed relation between the nut and the cutter frame. At its forward end the screw 16 is squared to fit a suitable wrench by which 5 it may be rotated to move the nut 18, and with it the cutter frame, relative to the base frame casting. The web 20 of the base frame casting is pierced by a slot 21 and in this is mounted a lock member 22 having a 10 notch at its lower end adapted to engage a hexagonal flange 23 formed on the adjusting screw 16 to hold it against rotation. When it is desired to change the adjustment of the cutter frame, the lock member 22 15 may be lifted and turned a quarter revolution, so that its broad head 24 may engage the edges of the slot 21 to hold it out of engagement with the flange 23. After the adjustment of the cutter arm the lock member 22 may be again dropped into place to secure the parts against accidental disarrangement.

This machine may be driven by any suitable motor actuated by any convenient 25 source of power, such as electricity, or compressed air. In the drawings I have shown for the purposes of illustration, an electric motor of the explosion proof type in which the motor 25, its starting box 26 and controlling resistance 27 are inclosed in a flame 30 proof casing to insure against the ignition of the gaseous atmosphere of a coal mine. Electric current for the actuation of the motor 25 is received through the conductor 35 cable 28. As this motor forms no part of the present invention, it need not be further described at this time. Attached to the operating shaft of the starting box is a spur gear 33 meshing with a similar gear 34 40 to offset the line of the extension shaft 35 which extends to the rear end of the machine and is provided with a hand wheel 36 convenient to the hand of the operator to control the operation of the motor. On the 45 frame of the motor 25 are formed feet 37 which are secured to suitable bosses of the base frame casting 1 to hold the motor in working relation with the operative parts of the machine.

50 To the armature shaft of the motor is secured the bevel pinion 38 which engages with the master gear 39 to drive the machine. This master gear 39 is attached by suitable machine screws 40 to the upper end 55 of the sleeve 41 which is journaled for rotation about the stationary vertical shaft 42. The lower end of the shaft 42 is screw threaded to the flange casting 43 riveted to the skid pan 4, and at its upper end it is 60 fastened in an aperture of the yoke casting 44 by a suitable cotter 45. The yoke casting 44 is riveted to the cover plate 46 which is bolted to the lugs 47 formed on the motor frame, thereby affording a rigid support for 65 the shaft and the gearing mounted thereon.

There are two brackets 48 attached to the under side of the cover plate 46, one at either side of the center line of the machine and upon these are mounted the thrust rollers 49 which engage the upper surface of 70 the rim of the master gear to hold it in contact with the pinon 38. Formed upon the shaft 42 near its upper end is a flange 42' between which and the boss 44' of the yoke casting 44 is positioned a ball bearing 75 thrust collar 50 which projects laterally beyond the periphery of the flange 42' and of the boss 44'. The lower surface of the projecting portion of the thrust collar 50 is engaged by a shoulder 41' of the sleeve 41 and 80 its upper surface is engaged by a flange 39' of the master gear 39. By this arrangement of parts the weight of the sleeve 41 and of the gear parts attached thereto is carried upon the ball bearing 50 by the flange 39' 85 and the upward thrust of the worm 64 and the master gear 39 is resisted by the ball bearings 50 against the yoke casting 44.

Rotatably mounted upon the lower end of the sleeve 41 is a sprocket wheel 52 which 90 engages the cutter chain 12 to drive it. Upon the upper side of the sprocket wheel 52 are formed clutch teeth 53 engageable with the teeth of the clutch member 54 splined to the sleeve 41. A circumferential 95 groove 55 in the clutch member 54 is engaged by a supporting yoke 56 which is carried by the shifting lever 57 in a manner common to clutch shifting mechanism. This shifting lever 57 is supported on trunnions 58 in bearings of the base frame casting 1 and has an upstanding arm 59 connected through the rod 60 with the crank arm 61. The crank arm 61 is attached to a hollow shaft 62 supported at the rear end 100 of the machine in a manner to be later described, and provided with a hand lever 63 by which it may be rotated to rock the shifting lever 57 to slide the clutch 54 into or out of engagement with the sprocket 110 wheel 52.

Formed on the sleeve 41 is a worm 64 which meshes with the worm wheel 65 keyed to the horizontal power shaft 66. The shaft 66 is journaled in bearings 67 and 115 68 formed on the base frame casting 1. Provision is made for the lubrication of both the worm wheel 65 and the bearing 67 by an oil receptacle 69 belted to the bearing, and provided with apertures 70 and 71 positioned so as to deliver oil at the desired points.

Mounted upon the power shaft 66 and connectible thereto by a friction clutch 72 is a spur pinion 73 which meshes with the 125 spur gear 74 of the feeding mechanism gear train. This friction clutch 72 is of the well known multiple disk type consisting of the driving member 75 keyed to the shaft 66 and the driven member 72 attached to the 130

extension 76 of the pinion 73, which are connectible together by the friction disks 77 in the manner common to such clutches. The disks 77 are adapted to be pressed by 5 the pressure plate 78 to produce the necessary friction between the disks to cause the member 75 to drive the member 72. Attached to the clutch member 72 by suitable machine screws 79 is a circular cover plate 10 which entirely closes in the mechanism 15 of the clutch. Screw threaded through the center of the plate 80 extends a pressure screw 81 the inner end of which impinges upon the pressure plate 78, and to the outer end of which is fixed a hand wheel 82 by which the screw may be rotated to vary the pressure upon the disks 77 to control the action of the clutch.

The feeding mechanism comprises a power 20 actuated winding drum 83 adapted to wind the feed rope 84, one end of which is fixed to a suitable anchor, to draw the machine over the floor of the mine to feed the cutter mechanism to its work. The drum 83 is 25 provided with flanges 85 to confine the rope as it is wound up, and one of these flanges is perforated at 86 to pass the end of the rope to be secured between the converging lugs 87 by the wedge 88. The drum 83 is 30 journaled on the horizontally projecting stud shaft 89 fixed to the main frame casting 1. Formed on the inner surface of the drum 83 is an internal gear 90 which meshes with the spur pinion 91 fixed to the outer 35 end of a counter shaft 92 journaled in cylindrical bearing 93 formed of the main frame casting 1. At the other end of this shaft 92 is fixed a hub 94 upon which the spur gear 74 is rotatably mounted. An oil res- 40 ervoir 95 formed in the frame casting supplies oil for the lubrication of the bearing 93. Formed on the hub 94 is a flange 96 having apertures 97 adapted to register with similar apertures of the web 98 of the gear 45 74 and adapted to receive the pins 99 of the clutch 100 to connect the gear 74 and the hub 94 together.

The clutch member 100 is rotatable upon and slidable along the outer surface of the 50 bearing 93 and is provided with an annular groove 101 by which it is connected to the clutch shifting mechanism in the manner common to such mechanism. The lever 102 of this clutch shifting mechanism extends to 55 a point convenient to the hand of the operator, and affords means to engage or to disengage the pins 99 with the flange 96. By the arrangement of parts above described the friction clutch affords means to drive 60 the feeding devices which, by the slippage of the disks, insure the machine against overloads, and the pin clutch allows the drum to be disconnected from the driving gears and friction clutch to facilitate un- 65 winding of the rope 84 when adjusting the

machine preparatory to cutting the coal. Guide sheaves 84^a, 84^b, 84^c and 84^d are conveniently positioned about the frame of the machine to lead the feed rope 84 in any desired direction.

Rotatably mounted upon the shaft 66 is a hub 103 having a flange 104 at the periphery of which is formed a laterally projecting cylindrical extension 105 which forms the driven member of a multiple 75 disk friction clutch, the driving member 106 of which is keyed to the shaft 66 and is connectible with the driven member 105 by the disks 107 in the manner common to such clutches. To the end of the extension 105 is secured by suitable machine screws 108, a circular cover plate 109 by which the clutch mechanism is completely inclosed. Upon this cover plate is formed a hub 110 having a bearing upon the shaft 85 66 to afford a broad support for the clutch member 105. Positioned adjacent the clutch members 105 is a disk 111 having a hub 112 journaled upon the shaft 66. Formed on the periphery of the disk 111 is a winding 90 drum 113 upon which is wound a rope 114 the free end of which is adapted to be attached to a suitably placed anchor outside of the machine. The rope 114 serves the double purpose of handling the machine 95 about the room to place it preparatory to cutting the coal, and to balance the reaction of the cutting mechanism to maintain its angular relation to the coal face during the cutting operation as will be fully described 100 hereinafter. The drum 113 and friction clutch member 105 may be connected together by a pin clutch comprising a ring 115 slidable longitudinally of the hub 112 and having pins 116 extending through 105 apertures in the disk 111 to engage with registering apertures in the flange 104. This pin clutch is controllable by a shifting lever 117 adapted to be moved by the rotation of the shaft 118 journaled in suitable bearings 110 of the machine frame and provided with a cross bar handle 119 for its convenient manipulation.

On the outer surface of the hub 110 is formed a screw thread 120 and to this is 115 fitted a ring 121 adapted to be moved by its rotation relative to the hub 110 nearer to or farther from the cover plate 109. Within a recess of the ring 121 is mounted a ball bearing 122 and upon this bearing impinges 120 the ends of a plurality of pins 123 which extends through apertures of the cover plate 109 and engage the pressure plate 124 to transmit the pressure of the ring 121 to the disks 107 of the friction clutch. On the 125 outer surface of the ring 121 are formed gear teeth which engage the pinion 125 attached to the shaft 126 journaled in bearings 127 and 128 formed at the rear end of the main frame casting 1. The shaft 126 130

is provided with a hand wheel 129 positioned convenient to the hand of the operator to afford means to rotate the ring 121 and thereby control the drum 113. The hollow shaft 62 which forms a part of shifting mechanism by which the clutch 54 is controlled, is supported upon and rotatable about this shaft 126. Guide sheaves 130 and 131 are conveniently positioned upon the frame of the machine to lead the rope 114 to the drum 113.

Formed in the outer flange 132 of the drum 113 are a plurality of apertures 133 adapted to engage with the teeth of a pinion 134 mounted upon a shaft 135 journaled in suitable bearings of the machine frame the projected end of which is squared to fit a convenient wrench by which the shaft may be rotated to rotate the drum 113 to wind the rope 114.

During the adjustment of the parts preparatory to moving the machine or to cutting the coal, the pin clutch may be moved to disconnect the drum 113 from the friction clutch member 105 to allow the free unwinding of the rope 114 to attach it to a suitably placed abutment. When such attachment has been effected the shaft 135 will be rotated to rotate the drum 113 to wind up the slack rope after which the pin clutch may be moved to reconnect the drum with the friction clutch. Fixed to the sleeve 41 is a bevel gear 138 which engages a bevel pinion 139 to drive the shaft 140 journaled in bearings 141 and 142 of the machine frame. Oil cups 143 and 144 formed on these bearings afford means for their lubrication. The shaft 140 projects beyond the side of the machine frame and has fixed to its overhanging end a sprocket wheel 145 adapted to be connected by a suitable driving chain with the axle of the truck upon which the machine is moved from place to place, to provide power for such movement. A description of the truck is not necessary at this time as it forms the basis of my co-pending application of even date.

Formed in the metal of the base frame casting 1 is an oil receptacle 146 having an outlet 147 fitted with a plug valve to which is attached a crank arm 148 connected with a hand rod 149 extending to a point convenient for its manipulation. By means of this plug valve the flow of oil from the receptacle may be regulated. The outlet 147 is so positioned relatively to the cutter chain 12 that oil flowing thereon will lubricate its articulation, and be carried into the guide ways of the cutter arm. In the limited space in which such machines must operate in thin veins of coal it is often impossible for the operator to reach across the machine from one side to another and the adjustment of parts on the opposite side of the machine compels him to crawl on hand and

knees around the rear end of the machine. To overcome this difficulty I have grouped the controlling devices at a point which is within convenient reach of the hand of the operator when he is in a position to observe the advance of the cutting mechanism into the coal. By reference to Fig. 1 of the drawings it will be seen that the hand wheel 82 controlling the winding of the feed rope 84, the hand wheel 129 controlling the winding and unwinding of the rope 114, the hand wheel 36 of the motor starting box 26 and the clutch lever 53 of the cutter chain sprocket clutch 54 are grouped at the left hand outer corner of the machine thus placing all of the devices subject to manipulation during the cutting operation at the point most convenient to the operator while observing the action of the cutting mechanism.

The operation of the machine is as follows: The machine having arrived at the room which is to be cut, and the truck 153 advanced to the desired position for unloading, a jack 154 is placed as in Fig. 9, the handling rope 114 is drawn out from the drum 113 passed around the sheave 137 fixed at the corner of the machine frame, the snatch block 155 is attached to the forward part of the cutter frame and the rope passed around the sheave 156 and attached to the jack. The motor is then started and the hand wheel 129 manipulated to cause the rotation of the drum 113 to wind the rope 114, thereby pulling the machine off the truck 100 and dragging it across the room in the direction of the jack. The machine can thus be placed in any desired position. After the completion of the cut the machine may be drawn to the truck and re-loaded thereon by connecting the handling rope to suitable points of attachment on the truck and the clutch manipulated to wind the rope.

When the machine is to be sumped at the right side of the room preparatory to cutting the coal from right to left, it will be placed as shown in Fig. 10. The jacks 157 and 158 will be set adjacent the coal face, one at either side of the machine. The pin clutch 100 will be disengaged to allow the drum 83 to freely revolve and the rope 84 drawn out and attached to the jack 157. The pin clutch 100 will then be reengaged to connect the drum 83 with the power elements of the machine. The rope 114 will then be drawn out from the drum 113 and attached to the jack 158. The motor will then be started and the clutches manipulated to wind both ropes to draw the machine longitudinally to force the cutter arm 9 into the coal. Owing to the gear arrangements the speed of winding the handling rope 114 is about eight times as fast as that of the feed rope 84, but by proper manipulation of the hand wheel 129 sufficient slippage may be

allowed in the disks of the clutch 105 to maintain a uniform rate of winding of the two ropes and pull the machine straight into the coal. By this arrangement the direction 5 of cutting may be accurately controlled, the clutch 105 being tightened or loosened as necessity may direct.

When the machine is fully sumped the jacks 157 and 158 will be removed, a jack 10 159 placed at the left hand side of the room adjacent the coal face, as shown in Fig. 11, and the feed rope 84 passed around the sheave 84^a and attached to the jack. A second jack 160 will be set at the right hand 15 side in alinement with the rear end of the machine and the handling rope drawn out from the drum 113 and attached to the jack. When now the motor is started, the hand 20 wheel 82 will be set up to wind the feed rope and the hand wheel 129 manipulated to cause the friction clutch to exert a winding torque on the drum 113, thus immediately taking up all the slack in the rope 114 and tending to swing the outer end of the 25 machine toward the right. The adjustment of the friction clutch in the drum 113 will be such that the resistance to the advance of the outer part of the machine will balance the resistance of the coal to the progress of 30 the cutting mechanism and thus counteract the tendency of the feed rope to swing the machine to the left. The machine will thus be fed across the room from right to left as shown in Fig. 11.

35 Should the floor of the mine room slope away from the face, the jack 160 will be placed close to the face to produce a forward strain on the rope 114 to counteract the tendency of the machine to slip away 40 from the face. It is often the case, that, even when the floor of the room is perfectly level, there will be a tendency for the machine to work out of the coal. This tendency may be overcome by placing the jack 160 45 more or less near to the face to produce the desired balancing effect.

50 While undercutting along the face of the coal it becomes desirable at times to positively swing the outer end of the machine rearward so as to quickly change the angle 55 of the machine to the coal face. Thus in case a hard deposit of coal is encountered, it may be desirable to swing the machine so that the cutter may engage the coal, or obstruction, along more advantageous lines of 60 attack to effect the cutting through or dislodgment of the obstruction. In any such case, the rearward swinging of the outer end of the machine can readily be effected 65 by first rotating the hand wheel 82 in the direction to loosen the clutch and relieve the strain on the rope 84 and allow it to be drawn out from the drum 83, and then turning the hand wheel 126 to cause the drum 113 to wind the rope 114. When the de-

sired angle has been attained the hand wheels 82 and 129 will be manipulated to restore the former conditions of winding and the machine will be advanced in the new angular relation to the face of the coal. 70 After the obstacle has been cut through or torn out the hand wheel 129 may be manipulated to release the rope 114 and allow the rear end of the machine to swing to the left to restore the proper angle. 75

In Fig. 12 I have shown an alternative method of making the summing cut wherein the machine is placed adjacent to and parallel with the face of the coal, the forward end of the cutter arm close to the right hand 80 rib. The jacks are set and the ropes connected precisely as in Fig. 11. When now the machine is started the clutches are manipulated to cause the rope 114 to draw the machine forward and the rope 84 to retard 85 such movement, the result being that the machine will be rotated about the sheave 84^a to make the summing cut as shown by the dotted lines of Fig. 12.

Furthermore when it is considered that 90 the two clutch hand wheels 82 and 129 can be set in an indefinite number of positions, ranging from that at which the clutch disks move freely in relation to each other to that in which the friction between the disks is 95 increased until the disks seize and stop relative movement, it will be understood that by suitable manipulation of the two hand wheels the tension on the feed rope 84 can be varied as desired to control the rate of 100 feed, and at the same time the tension in the tail rope 114 can be varied as desired to maintain the machine at any desirable angle to the face of the coal.

The above described method of operation 105 is thought to be necessary to a complete understanding of the invention they being dependent upon the particular arrangement of parts and therefore peculiar to this machine. It is obvious, however, that there are many 110 methods of operation and handling, which are common to machines of this class, and applicable to this machine, but a description of them is not thought to be necessary at this time. 115

What I claim is—

1. In a mining machine, the combination with a main frame adapted to rest upon and slide over the floor of the mine, a motor carried by the main frame, a motor controller 120 positioned to be operable from the operating side of the machine, cutting mechanism carried by the main frame, feeding devices including a winding drum and a rope windable thereon, guiding devices including a second winding drum and a second rope windable thereon, power transmitting devices including clutch mechanism operable from the operating side of the machine connecting the cutting mechanism with the 125 130

motor, power transmitting devices including a friction clutch operable from the operating side of the machine connecting the first mentioned drum with the motor, power transmitting devices including a second friction clutch operable from the operating side of the machine connecting the second mentioned drum with the motor, and clutch mechanism independent of said friction 5 clutches and operable from the operating side of the machine adapted to release either or both winding drums from the power transmitting devices.

2. In a mining machine, the combination 15 of a main frame adapted to rest upon and slide over the floor of the mine, a motor carried by the main frame, an endless chain cutting mechanism projecting horizontally from the main frame, two winding drums 20 mounted upon the main frame, ropes windable thereon, trains of gearing each including a friction clutch to connect each drum with the motor to wind its rope, and positively acting clutch mechanism interposed 25 between each winding drum and its gear train to permit the release of said drums from said gear trains adapted to disconnect each drum from its gear train to allow the free unwinding of its rope.

3. In a mining machine, the combination 30 of a main frame adapted to rest upon and slide over the floor of the mine, a motor carried by the main frame, an endless chain cutting mechanism projecting horizontally 35 from the main frame, a winding drum mounted upon the main frame, a rope windable thereon, a train of gearing including a friction clutch to connect the drum with the motor to wind the rope at a relatively low 40 speed, clutch mechanism independent of said friction clutch adapted to disconnect the

drum from the said gear train to allow the free unwinding of the rope, a second winding drum mounted upon the main frame, a rope windable thereon, a gear train including a friction clutch adapted to connect the second mentioned drum with the motor to wind the second mentioned rope at a relatively high speed or to resist the unwinding thereof, and positively acting clutch mechanism interposed between said drum and said gear train.

4. In a mining machine, the combination 45 with a main frame, cutting, feeding and guiding devices carried by the main frame, a motor mounted on the main frame, a shaft rigidly supported by the main frame, a sleeve rotatable upon the shaft, gearing connecting the motor with the cutting, feeding and guiding devices having elements 50 attached to the sleeve which tend to move said sleeve longitudinally of said shaft, and an antifriction thrust collar attached to the stationary shaft and engaging the sleeve to hold it against longitudinal movement in 55 either direction.

5. In a mining machine, the combination 60 with a main frame, a vertical shaft rigidly supported in the main frame, a sleeve rotatable upon said vertical shaft, upwardly 70 thrusting gearing attached to said sleeve, and an antifriction thrust collar attached to said vertical shaft and engaging said sleeve to both support the weight of the sleeve and to resist the upward thrust of the 75 gearing.

In testimony whereof I affix my signature, in the presence of two witnesses.

NILS D. LEVIN.
